US0D1028922S

(12) **United States Design Patent** (10) **Patent No.:** **US D1,028,922 S**
(45) **Date of Patent:** **** May 28, 2024**

(54) **MOBILE PHONE**

(71) Applicant: **VIVO MOBILE COMMUNICATION CO., LTD.**, Chang'an Dongguan (CN)

(72) Inventors: **Jianguang Nie**, Chang'an Dongguan (CN); **Feng Yuan**, Chang'an Dongguan (CN); **Jing He**, Chang'an Dongguan (CN)

(73) Assignee: **VIVO MOBILE COMMUNICATION CO., LTD.**, Chang'an Dongguan (CN)

(**) Term: **15 Years**

(21) Appl. No.: **29/748,458**

(22) Filed: **Aug. 28, 2020**

(30) **Foreign Application Priority Data**

Mar. 2, 2020 (CN) 202030065539.1

(51) **LOC (14) Cl.** **14-03**

(52) **U.S. Cl.**

USPC ..... **D14/138 G**

(58) **Field of Classification Search**

USPC ..... D14/138 R, 138 G, 138 AA, 138 AB, D14/138 AC, 138 AD, 138 C, 248, 203.1, D14/203.3, 203.4, 203.7, 388, 389, 432, D14/439, 426, 348, 341, 496; D21/329; D10/50

CPC G06F 1/1613; G06F 1/1686; G06F 1/1626; G06F 1/1692; G06F 2200/1633
